UNITED STATES PATENT OFFICE.

PAUL A. BANCEL, OF NEW YORK, N. Y., ASSIGNOR TO HIMSELF, AND GEORGE H. GIBSON, OF UPPER MONTCLAIR, NEW JERSEY.

CONDENSING APPARATUS.

1,114,333.

Specification of Letters Patent. Patented Oct. 20, 1914.

Application filed November 29, 1912. Serial No. 734,049.

To all whom it may concern:

Be it known that I, PAUL A. BANCEL, a citizen of the United States of America, residing in the city, county, and State of New York, have invented certain new and useful Improvements in Condensing Apparatus, of which the following is a true and exact description, reference being had to the accompanying drawings, which form a part thereof.

My present invention relates to condensing apparatus such as the surface condensers employed for condensing the exhaust steam from steam motors, in which the vapor to be condensed is passed into a condensing chamber and into contact therein with tube or other walls exposed externally to the condensing chamber to a cooling fluid.

The object of the present invention is to improve condensing apparatus of the kind described by providing novel and effective means for regulating the distribution of steam throughout the condensing chamber, and for aiding in the removal from the condensing chamber of the air or other non-condensable vapor or gas tending to accumulate therein, with the ultimate object of increasing the efficiency of the condensing apparatus and of facilitating the maintenance of a high vacuum when this is desired.

I accomplish the desired results by providing means for so directing jets of steam, which may be either high pressure steam or low pressure steam as conditions make desirable, into appropriate portions of the condensing space, to thereby produce the desired circulation of the air or other non-condensable gas or vapor as well as of the steam to be condensed. The use of such circulation controlling provisions not only adds to the efficiency of surface condensing apparatus of practically every type, but makes it possible to operate condensing apparatus with a general direction of flow therethrough which is independent of gravity, and of the relative densities of steam and non-condensable vapors or gases at varying temperatures.

The invention is of particular utility in connection with condensers of relatively large size, and the modern development of power plants tends constantly toward units of larger size. As the size of a condenser unit increases the paths to be traversed by the steam and air increase in length, and the

tendency of air or rather an air-steam mixture rich in air to collect and stagnate, and thereby prevent the proper distribution of steam in certain parts of the condensing space also increases.

The various features of novelty which characterize my invention are pointed out with particularity in the claims annexed to and forming a part of this specification. For a better understanding of the invention, however, and of the advantages possessed by it, reference should be made to the accompanying drawings and descriptive matter in which I have illustrated forms in which my invention may be embodied.

Of the drawings: Figure 1 is an elevation partly in section of one form of condensing apparatus embodying my invention. Fig. 2 is a partial sectional elevation taken on the line 2—2 of Fig. 1. Fig. 3 is a transverse sectional elevation of a modified form of condensing apparatus; and Fig. 4 is a transverse sectional elevation of a third form of condensing apparatus embodying my invention.

In the drawings, and referring first to the construction shown in Figs. 1 and 2—A represents the shell or housing of a surface condenser of well known type, provided with a steam inlet A' opening to the top of the condensing chamber, and a water outlet A² opening from the bottom of the condensing chamber and with air outlets A³ leading from the sides of the condensing chamber adjacent its bottom. B represents the usual cooling water tubes passing through the condensing chamber. As shown, the tubes are grouped to provide a central steam space A⁴ in the condensing chamber and vertical channels A⁵ at the sides of the condensing chamber. Inclined rain plates or baffles are arranged at various elevations in the condensing chamber. These convey the water of condensation formed in the inter-space immediately above each plate to the adjacent side channel A⁵, thereby preventing the water from dropping down on the subjacent tubes B. They also provide definite flow channels. D represents steam jet nozzles disposed at appropriate places in the condensing chamber for effecting the desired circulation of the steam to be condensed and of the air or other non-condensable gas or vapor admixed therewith.

As shown in Figs. 1 and 2, the nozzles D are directly connected to and receive steam from pipes E, each of which is provided with a plurality of nozzles D. Each pipe E is connected by an individual valved connection D' to the steam supply piping F, so that the relative discharge of steam through the nozzles located in different portions of the condensing chamber may be regulated or entirely cut off as desired. To increase the aspirating effect of the steam jets issuing from the nozzles D baffles G may be employed as shown. In the condenser shown in Figs. 1 and 2, the outlets A³ for air and other non-condensable gas or vapor are connected to auxiliary condensing and vacuum producing apparatus which as conventionally illustrated comprises a small supplemental condenser H and an ordinary dry air pump I. B' represents cooling water tubes which may be located adjacent the air outlets A³ to cool the fluid passing through the latter. The steam supplied by the pipe F may be live steam from any readily available source, or it may be low pressure steam, drawn for instance, from an intermediate stage of a turbine where, as in the particular construction shown in Figs. 1 and 2, the pressure in the condensing chamber is intended to be below that of the atmosphere. It is to be understood, however, that the invention is not limited to use in condensing apparatus in which a vacuum is maintained in the condensing chamber, but may also be employed in connection with closed feed water heaters or evaporators and like apparatus in which the pressure within the condensing space is at or above atmospheric pressure. To obtain an effective distribution of the steam in the condensing chamber, and to materially aid in the removal of air and uncondensed gas or vapor by the use of steam jets in accordance with the present invention, requires but a relatively small amount of steam to be discharged by the jet nozzles and results in very greatly increasing the efficiency and capacity of the condensing apparatus.

In the modified form of my invention shown in Fig. 3, A A represents the condenser casing, A¹⁰ the steam inlet to the upper end of the condensing chamber, A¹¹ the water of condensation outlet, and J the outlet for air and other uncondensed gas or vapor. In this form of my invention the jet nozzles D A are arranged so that in conjunction with the baffles C A which extend like the blades of a fan from the pipe J as a center, they cause the steam and other gaseous fluid to flow downward and toward the center of the condensing chamber.

The form of my invention shown in Fig. 4 is a variation of that shown in Fig. 3, in

which the nozzles D B and baffles C B are so disposed that the circulation is toward the center of the top of the condensing chamber. As shown in Fig. 4, the steam inlet A¹⁰ opens to the condensing chamber A B at the bottom, while the outlet A¹¹ for air and other uncondensed gas or vapor leads from the top of the condensing chamber. With this arrangement the water of condensation passing out of the condensing chamber at the bottom through the outlet A¹² approximates the maximum possible temperature: to wit, that of the incoming steam, with which it is in contact, while the air and other gas or vapor passing out through the air outlet A¹³ is well cooled. These are important advantages, since where the water of condensation is used as boiler feed water, as is usual, it adds to the efficiency of the plant, of course, to have it at the maximum temperature possible, while it is desirable to have the gaseous fluid passing out of the condenser as cool as possible, for the reason, among others, that it reduces the duty imposed upon the dry air vacuum pump. Furthermore, the construction shown in Fig. 4 permits the condenser to be located on the same floor level with the turbine or other steam engine from which it receives steam, and to be connected thereto by relatively short and simple exhaust steam connections. These advantages are highly desirable, but ordinarily are secured at a sacrifice of efficiency, because air which collects in the top of the condenser being heavier than steam, tends to flow down, rather than upward toward the air outlet.

Certain features of invention disclosed but not claimed herein are claimed in my co-pending application Serial No. 734,050 filed of even date herewith.

While in accordance with the provisions of the statutes I have illustrated and described the best forms of my invention now known to me, it will be apparent to those skilled in the art that changes may be made in the form of the apparatus disclosed without departing from the spirit of my invention, and that under some conditions certain features of my invention may be used without a corresponding use of other features.

Having now described my invention, what I claim as new and desire to secure by Letters Patent, is:

1. In condensing apparatus of the surface condenser type, the combination with the condensing chamber and its main steam inlet, and water, and air and vapor outlet provisions, of means for discharging jets of steam into said condensing chamber to thereby regulate the distribution therein of the steam entering through said main inlet, and the discharge of air and vapor.

2. In condensing apparatus of the surface condenser type, the combination with the

condensing chamber and its main steam inlet, and water, and air and vapor outlet provisions of separately regulable jet devices for discharging jets of steam into said condensing chamber to thereby regulate the distribution therein of the steam entering through said main inlet, and the discharge of air and vapor.

5 3. In a surface condenser the combination with a condensing chamber having a steam inlet opening to, and a water of condensa-

tion outlet opening from the bottom of said chamber and an air and vapor outlet opening from the top of said chamber and having tubes for cooling water traversing said 15 chamber, of means for discharging into said chamber jets of steam directed toward said air and vapor outlet.
